Primary Examiner — Sheryl Lane(74) *Attorney, Agent, or Firm* — Suzanne Kikel, Patent Agent**CLAIM**

The ornamental design for a sand and grass seed dispenser for repairing divots, as shown and described.

DESCRIPTION

FIG. 1 is a front perspective view of a sand and grass seed dispenser for repairing divots.

FIG. 2 is a front view thereof.

FIG. 3 is a rear view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines represent portions of the article and form no part of the claimed design.

1 Claim, 7 Drawing Sheets(56)
